His Attorney.

UNITED STATES PATENT OFFICE.

CHARLES C. WAIS, OF CINCINNATI, OHIO, ASSIGNOR OF ONE-HALF TO ALBERT C. WAIS,
OF WYOMING, OHIO.

SAFETY WINDOW SEAT.

Application filed March 19, 1925. Serial No. 16,763.

My invention relates to safety window seats arranged to be fastened to a window-sill so that a person cleaning the windows may have a secure seat while cleaning the outer faces of the windows.

It is the object of my invention to provide such a device to suit various locations and which may be readily secured in place at the window; further, to provide novel means for fastening the frame of the window-seat to the window-sill; further, to provide novel means for safeguarding the user while in the seat; and, further, to provide novel construction and arrangements of parts whereby to protect the user and provide space for his implements.

The invention will be further readily understood from the following description and claims, and from the drawings, in which latter:

Fig. 1 is a perspective view of my improved device, shown in connection with a window, partly broken away.

Fig. 2 is a vertical section of the same, taken on the line 2—2 of Fig. 1.

Fig. 3 is a plan view of my improved device in folded relation.

Fig. 4 is a side elevation of the same.

Fig. 5 is a detail of one of the releasable articulations, showing the same in section on the line 5—5 of Fig. 2.

Fig. 6 is a side elevation of the same.

Fig. 7 is a vertical cross-section of the same, taken in the plane of the line 7—7 of Fig. 2.

Fig. 8 is a side elevation, partly in section and partly broken away, showing a modification of the securing means for the sliding block; and,

Fig. 9 is a detail of the same, taken on the line 9—9 of Fig. 8.

The seat-frame comprises side-bars 11, the rear ends of which are bent upwardly, as shown at 12. Holding means 13 are provided at the front ends of the bars for co-acting with the inner ledge 14 of the window sill 15. These holding means are shown as clamps, each having a rearwardly projecting jaw 16, on a threaded shank 17, received through a bearing 18, at the front end of the side-bar 11, a wing-nut 19 clamping the inner ledge of the window sill between said jaw and said side-bar. There is one of these holding means at each side of the seat-frame.

The seat-frame further comprises a lower

side bar 21, at each side thereof, having an upward projection 22 at its rear end, fixed to the upward projection 12, as by rivets 23. Side-straps 25, 26, are secured to the upper and lower side-bars at each side of the seat-frame, as by rivets 27, 28, and form rigid connections between said side-bars for spacing the side-bars apart. Cross-straps 31 extend between the lower side-bars and are fixed to said respective side-bars, as by rivets 32.

A seat 35, shown of corrugated sheet-metal, is located between the upper side-bars. Its side edges 36 are bent upwardly. The side-bars are exemplified as channel-bars, the upward bends at the respective sides of the seat being received in the channels and secured to the channel-bars, as by the rivets 37. Truss-braces 38 are located between the cross-straps 31 and the seat, being preferably secured to both, as by the rivets 39, 40.

Blocks 45 cooperate with the outer edge of the window-sill, there being one of these blocks at each side of the seat-frame. Each of these blocks is provided with a rabbet 46 at its front lower portion, forming an upper wall 47, which is shown slanting upwardly and forwardly, and an abutment wall 48, these walls co-operating respectively with the upper face and the outer face of the outer ledge 49 of the window-sill, for leveling the window-seat and to cooperate with the window-sill for holding the seat-frame in position.

Means are provided for holding my improved device upon the window-sill to prevent the front clamps from slipping away from the inner edge of the window-sill. The blocks are slideable in guideways 51, shown formed of sheet metal walls, forming channels in which the blocks may slide, the sheet metal walls being secured to the upright straps 25, 26. The straps are shown provided with laterally outwardly extending bulges 52, in which the channel-frames are received.

Referring to Figs. 1 to 7 inclusive, each of the blocks has a link 55 articulated therewith on a bolt 56, the link being received in a recess 57 at one side of the block, and a nut 58 received over the threaded end of the bolt being received in a recess 59 at the other side of the block.

A rocker pin 61 is journaled in the lower

side-bar 21, and has an arm 62 fixed thereto, this arm being articulated at 63 with the link 55, the arm and the link forming a toggle link structure between the seat-frame and said block. A handle-arm 65 is also fixed to the rocker-pin, and has a handle 66 thereon. When the handle is moved upwardly, the block is propelled rearwardly, for relieving clamping action on the outer portion of the 10 window-sill. When the operating arm is moved downwardly, the toggle-link is operated to force the block toward the window-sill. When the block is in clamped relation, the axis of the articulation 63 has passed a 15 right line between the axes of the articulations 56, 61, for locking the toggle-links and preventing retraction of the blocks by rearward pressure upon the blocks. When the toggle-links are in this relation, the toggle-link 55 rests upon the lower wall of the recess 57 for limiting downward movement of the toggle-links.

A back 71 is pivoted to the seat-frame, for instance, on pivot-pins 72, in bearings 73, 74, 20 respectively on the rear ends of the side-bars 11 of the seat-frame and the lower ends of side-bars 75 of said back. A cross-wall 76 connects said side-bars of the back, and is rigidly fixed thereto, as by rivets 77 between 25 the side edges of said cross-wall and one of the flanges of each of the side-bars 75, these side-bars being exemplified as channel-bars. The back may be provided with a covering 78, for instance of canvas, held to the cross-wall of the back by lacings 79.

A covering 81 is also preferably provided for the seat, laced at its respective front and rear ends to said seat by lacings 82.

Upright bars 85 extend upwardly from 40 the seat-frame, and are preferably pivoted to said seat-frame on pins 86, which are received through the lower ends of said upright bars and upward extensions 87 of the side-straps 25. There is one of these upright bars at each side of the seat. A link 88 at 45 each side of the seat connects the upright bar with the seat-frame, being articulated with the upright bar at 89 and with the seat-frame at 90.

50 The latter articulation is preferably releasable, and may comprise for instance a shank 91 pivoted in a hole 92 in an upward extension 93 of the side-strap 26, the shank having a wing handle 94 at one end and a laterally extending lug 95 at its other end. The lower end of the link is provided with a hole 96, from which a slot 97 extends. The lug is arranged to be received through the slot, whereupon the shank is turned for placing its lug across the wall of the hole, for holding the link in place.

55 A link 101 connects the upright bar with the back, preferably by articulations at 102, 103. One of these articulations, exemplified as the articulation 102, may be releasable, and

be an articulation similar to the articulation 90.

Flexible connections, shown as chains 105, have their respective ends secured to the link 101 and the seat-frame at each side of the 70 seat.

The construction of upright bars, links and flexible connections form sides for the seat, and hold the back securely in place when the device is in use, and are so arranged as to permit collapsing of the back and of the sides for convenient and compact 75 storing of the device.

Aprons 108 may depend from the link 101, being attached thereto by rings 109, and 80 be provided with pockets 110, in which the utensils, such as brushes, cloths, etc. used in window cleaning, may be contained.

Flexible connections 111 are arranged at the respective sides of the back between the 85 back and the respective side walls of the window opening. These flexible connections are shown as chains, having articulations 112 with the side-bars of the back. The front ends of the flexible connections are 90 provided with hooks 113, received through eyes 114 in eye-plates 115 secured to the side walls 116 of the window framing. The hooks are spring-latch hooks of usual construction.

I have in Figs. 8 and 9 shown a modification for the block securing means, in which the blocks have bolts 121 extending therefrom, the heads of the bolts being non-rotatively located in the blocks, and the threaded ends thereof extending through slots 122 in 95 the outer wall of the guideway 51, wing-nuts 123 being threaded over the bolts and clamping the blocks in place in cooperative relation with the window sill, or in released position.

100 The seat-frame may be provided with pads 125 for resting on the inner portion of the window-sill.

Means may also be provided for positioning the seat-frame between the sides of the 110 window opening, as by providing the same, preferably at each side of the seat frame, with a spacing block 127, pivoted to a lug 128 on the side-bar 11 by a pin 129, the heel 130 of the block being arranged to bear 115 compressingly upon the side wall 116 when the spacing block is in extended position between the side-bar and the side wall 116 of the window opening. When either or both of these spacing blocks are not in use they 120 may be swung lengthwise alongside the side-bars. Spacing blocks of different sizes may be used for window-openings of different widths.

125 When the device is not in use, the upright bars and links and back of the window-seat may be arranged lengthwise with relation to the seat, and the aprons and flexible connections laid upon the back, for forming a compact structure and taking up little room. 130

Such relation of the parts is exemplified in Figs. 5 and 6, in which the releasable connections 90, 102, are released for swinging the back forwardly so as to be arranged substantially parallel with the seat. The links 88 and the upright bars are collapsed for lying alongside the seat-frame, and the links 101 are arranged alongside the back.

The flexible connections 105 and 111 are laid upon the back, and the aprons are laid upon the flexible connections.

My improved device may be compactly arranged for carriage and for storage; it is strong and durable, and is readily attached to the window-sill. The frame parts, and the seat and back are preferably made of metal, sheet and bar metal being employed for the purpose of economical construction.

Having thus fully described my invention, what I claim as new, and desire to secure by Letters Patent, is:

1. In a device of the character described, the combination of a seat-frame provided with a yoke at its rear end, a seat in said seat-frame, means for releasably securing said seat-frame to a window-sill, a back the lower end of which is located between and pivoted to the rear ends of the sides of said yoke, an upwardly extending upright bar at the middle of each side of said seat-frame, each of said upright bars pivoted at its lower end to the middle portion of one side of said seat-frame, a link for each of said upright bars having pivotal connection at its front end with the upper end of its upright bar and extending upwardly and rearwardly

and having pivotal connection at its rear end with the upper end of said back, a downwardly and forwardly extending link-brace at each side of said seat-frame, each of said link-braces having its rear end pivoted to the middle portion of one of said upright bars, the front end of each of said link-braces provided with a releasable articulation with one of the sides of said seat-frame, whereby upon release of said last-named articulation said link-brace and said upright bar are moved forwardly into parallelism with each other and with said seat-frame, and said back is arranged to be swung forwardly into parallelism with said seat-frame between said sides of said yoke of said seat-frame, and flexible means between said first-named link and said seat-frame forming side walls for said seat.

2. In a device of the character described, the combination of a seat-frame, rearwardly projecting holding means at the front end of said seat-frame arranged for being received under the inner ledge of a window-sill, said seat-frame provided with guideways at its respective sides, blocks in said guideways arranged to cooperate with the window-sill, and means for moving said blocks in said guideways toward and from said window-sill comprising toggle-links and an arm for operating the latter, said toggle-links having articulations at their respective ends with said seat-frame and said blocks.

In testimony whereof, I have hereunto signed my name.

CHARLES C. WAIS.
